UNITED STATES PATENT OFFICE.

HENRY F. HILDEBRANDT, OF MAXWELL, TEXAS.

PLOW.

1,166,207.

Specification of Letters Patent.

Patented Dec. 28, 1915.

Application filed July 24, 1915. Serial No. 41,747.

To all whom it may concern:

Be it known that I, HENRY F. HILDEBRANDT, a citizen of the United States, and a resident of Maxwell, in the county of Caldwell and State of Texas, have invented a new and useful Improvement in Plows, of which the following is a specification.

My invention is an improvement in plows, and the invention has for its object to provide a plow or lister adapted for use as a riding or a walking plow, wherein a wheel supported frame is provided, and a plow supporting frame so connected that they may be separated to permit the use of the plow as a walking or a riding plow.

In the drawings: Figure 1 is a side view of the improved plow complete, Fig. 2 is a top plan view, Fig. 3 is a longitudinal vertical section, Fig. 4 is a perspective view of the plow supporting frame detached, and Fig. 5 is a horizontal section of the plow supporting frame.

In the present embodiment of the invention a wheel supported frame is provided, the said frame being substantially triangular and comprising an arch axle consisting of a body 1 and laterally offset spindles 2 upon which are journaled wheels 3. Plates 4 are connected at their rear ends to the vertical portions 5 of the axles, that is, to the integral connections between the body and the spindles. Each of the said plates 4 is connected to a C-shaped plate, comprising a body 6 and upper and lower arms 7 and 8.

A U-shaped brace or bracket consisting of a body 9 and depending arms 10 is connected with the plates 4 just in front of the axle, the body 9 of the bracket being at the level of the body 1 of the axle, while the arms 10 depend to a connection with the plates 4.

A brace 11 connects the arm 7 of each of the C-shaped plates to the bodies of the bracket 9-10 and axle, the said braces being arranged with their wide dimensions vertical between the plates 6-7-8 and the bracket 9-10, and just in front of the body of this plate each brace is given a quarter turn as shown, and is lapped upon the under face of the body of the bracket 9-10, and on the under surface of the body of the axle. Each brace is secured to the body of the bracket 9-10 by a bolt and nut 12, and to the body of the axle by a U-shaped clip 13.

A bolt 14 extends transversely between the arms 7 of the two plates 6-7-8, and this bolt connects both braces to the plates.

An arbor 15 is arranged on the bolt between the arms 7 of the plates, and the said bolt is engaged by a nut 16 to hold the parts in place. A trailing wheel 17 is arranged at the front of the frame, the said wheel being journaled between the arms 18 of a yoke, comprising the said arms and a body 19. The body of the yoke has a journal pin 20, which engages a bearing block 21, held between the arms 8 of the plates 6-7-8, and the pin is secured in place in the bearing in the usual manner by a cotter pin and washer, as shown. The yoke is free to turn on the journal pin with the trailing wheel.

A seat 20^a is connected to one end of a spring plate 21, whose other end is secured to the body of the axle by means of the clips 13, and the said seat is to one side of the frame. A toothed sector 22 is secured to the body of the bracket 9-10 and to the body of the axle, as shown, and a lever 23 is pivoted near its lower end to a cross strap 24, which connects the body of the axle with the body of the bracket 9-10 at the center of the said body.

The lever is provided with latch mechanism 25, which co-operates with the teeth of the sector to hold the lever in adjusted position, and a link 26 connects the lever above its pivotal connection with one of the arms 27 of an angle lever, consisting of arms 27 and 28. The other arm of the elbow lever is pivoted by means of a bolt 29 between the C-shaped plates 6-7-8 at the junction of the arms 8 with the bodies of the plate, and this angle lever is double as shown, consisting of two sections arranged alongside each other and spaced apart except at the connection of the link 26 therewith. A roller 30 is journaled on a journal pin 31, extending between the two sections, and this roller is in engagement with the front end of the plow supporting frame, to be later described, for permitting the said front end to be adjusted by means of the lever 23.

The plow supporting frame which is also substantially triangular is arranged between the side plates 4 of the wheel supported frame, and this plow supporting frame consists of a center plate 32 and side plates 33. The side plates 33 are approximately parallel with the plates 4 of the wheel supported frame, and they are connected at their front ends by a species of casing 34. This casing is approximately triangular in form, consisting of upper and lower portions, which

are connected by vertical webs 35 at their front. Each of the side plates 33 has an angular portion 33^a at its front end extending inwardly at an obtuse angle with respect to the body of the plate, and the said front ends of the side plates extend into the casing 34, the angular portions 33^a being parallel with the webs 35.

Each of the angle portions has a bearing 10 at its forward end which engages a bolt 36 connecting the upper and lower plates of the casing. Other bolts 36^a connect the upper and lower plates of the casing in rear of the bolts 36, and the said bolts 36^a are arranged on opposite sides of the central plate. The webs 35 at opposite sides of the central plate have forwardly extending lugs 37, which lap upon the opposite faces of the central plate 32, and are secured thereto by 15 a bolt and nut 38.

The front end of the central plate 32 is offset upwardly as indicated at 32^a, and is provided with openings for permitting the engagement of draft apparatus. It is this 25 upwardly offset portion 32^a of the central plate that is engaged by the roller 30 before mentioned, and it will be evident when the lever 23 is swung rearwardly the roller 30 will be lifted, and will lift the front end 30 of the plow supporting frame as indicated in dotted lines in Fig. 3. The rear end of the said frame is also connected to the lever 23 to permit the same to be lifted.

A shaft 39 is journaled in the arms 10 of the bracket 9-10 in openings in the said arms, and it will be noticed that each arm has a series of openings indicated at 40, the openings of each arm being in register to permit the shaft to be adjusted vertically. 35 This shaft 39 has a radial arm 41, which is connected by a link 42 to the lower end of the lever 23 and the end of the link adjacent to the arm 41 has a series of openings 43 for receiving the bolt 44, which connects 40 the arm to the link. By reason of the openings 43 the distance between the lower end of the lever 23 and the arm 44 may be varied. The shaft 39 is provided near each end with a rearwardly extending arm 45, 45 and each arm has a slot 46 in its rear end.

A pair of cross bars 47 is arranged transversely of the plow supporting frame at the rear ends of the side plates 33, and the pairs of bars are connected at their ends by U-shaped clips 48, and bolts and nuts 49. Each of the clips 48 is arranged with its body vertical and with one arm extending above the upper cross bar and the other extending below the lower bar, and the bolts 49 are passed downwardly through registering openings in the arms of the clips and the ends of the bars, and are engaged by the nuts below the lower arms of the clips. 60

The upper bar 47 of the member has near 65 each end a pair of laterally spaced bearing

lugs 50, and each pair of lugs has registering openings. Each of the arms 45 extends between the adjacent pair of lugs, and the arms are pivoted to the lugs, the pivotal connection passing through the openings of 70 the lugs and through the slots 46 of the arms.

A plow beam 51 is pivoted to the rear end of each side plate at the front end of the beam, and each beam passes between the 75 bars 47. Each of the beams 51 has a bearing 52 at its front end, and each of the bearings is received between a pair of lugs 53 on the rear end of the adjacent side plate 33. The lugs extend from the upper and 80 lower edges of the side plates, and each lug has a series of openings as shown, for receiving the belt 54 which connects the beam to the lugs. The bolts 54 pass through the bearings 52 and through a pair of registering 85 openings in the lugs, the arrangement being such that the beams may swing laterally toward and from the central plate 32.

Since the beams 51 are between the members of the pair of bars 47 it will be evident 90 that when the lever 23 is swung to oscillate the shaft 39 the rear end of the plow supporting frame together with the beams 51 will be raised or lowered, depending upon the direction of oscillation of the shaft 39. 95

A beam 55 is connected with the central plate 32 by means of oppositely arranged clamping plates 56. These plates 56 are arranged on the outer sides of the beam and the plate respectively, and they are clamped 100 together by bolts and nuts 57, the bolts extending through openings in the ends of the clamping plates above and below the beam. The beam 55 inclines forwardly toward its lower end, and each of the beams 51 is arc-shaped, curving downwardly and forwardly at its lower end.

Each of the beams 51 is provided at its lower end with a series of openings 58 for receiving the journal pin on a disk, or for 110 permitting the connection of a plow indicated at 59 in Fig. 3. The journal pin of the disk may be engaged with either opening of the beam to permit some degree of adjustment.

A splitting or lister plow 60 is connected with the lower end of a double standard 62. The sections of the standard are spaced apart from each other, and the bolts and nuts 63 which connect the shank with the standard 120 are passed between the sections, the shank fitting against the front edges of the sections.

The sections of the standard extend on opposite sides of the beam, and each has an arc-shaped series of openings 65 at its upper end transversely of the section. A bolt 64 is passed through an opening in the beam and through one of the openings of the series 65 in the upper end of the standard, and a second bolt 66 is passed through registering 125

openings in the sections of the standard and in the lower end of the beam, the bolt 66 being below the bolt 65.

By means of the bolt 64 the plow may be 5 adjusted with respect to the beam. The beams 51 are moved toward and from each other by means of a lever 66, which is pivoted to a bracket 67, secured to the rear end of the central plate 32, and having a toothed 10 sector 68 above the said plate. The lever 66 has latch mechanism 69, coöperating with the teeth of the sector to hold the lever in adjusted position, and a link 70 connects the lever with a shoe 71, mounted to slide on the 15 central plate in front of the cross bars 47. The shoe has a pair of bearings 72 at each side of the plate, and a bearing plate 73 is secured to each beam on the inner face thereof of a little in the rear of the cross bars 47.

20 Each of the bearing plates has bearings 74 at its ends, and a plurality of pairs of bearing links 75 and 76 connect each bearing plate with the adjacent side of the shoe. The members of each pair of links are 25 spaced apart vertically, and are connected to the shoe and the bearing plate by bolts and nuts 77, which pass downwardly through the ends of the links and through the bearings 72 and 74. When the shoe 71 is moved 30 longitudinally of the central plate 32 by means of the lever 66, the angle between the links 75 and 76 and the plate 32 will be changed to move the beams 51 toward or from the central plate.

35 The U-shaped clips 48 are guide blocks, the bodies of the said clips moving in channel shaped guide members or plates 79, which are secured to the vertical members 5 of the axle by clips 79. Each of the clips 40 has a groove for receiving the vertical portion of the axle, and the ends of the clip are connected to the channel shaped guide by bolts 80. The lower ends of the guide members 79 are connected to the side plates 45 of the wheel supported frame by bolts 81. These guide members prevent longitudinal movement of the frames with respect to each other when the said frames are moved vertically.

50 The clips 48 move in the channel when the plow supporting frame is moved vertically by means of the lever 23. This lever 23 raises and lowers the plow supporting frame and the plows bodily, the roller 30 lifting 55 the front end. The rear end is lifted by the arm 45 of the shaft 39.

When it is desired to detach the plow supporting frame from the wheel supported frame, the wheel supported frame is lifted 60 to disengage the bodies of the clips 48 from the guide members 78. In order to permit this lifting movement the arms 45 are disengaged from the lugs 50. When now the rear end of the wheel supported frame is lifted 65 the clips will move downward in the guide

members until they pass out through the lower ends thereof. The wheel supported frame is now pushed forwardly and the offset portion 32^a of the central plate 32 rolls off the roller 30.

70

I claim:—

1. In combination, a wheel supported frame and a plow supporting frame detachably and adjustably connected therewith, the wheel supported frame comprising an 75 axle consisting of a body and spindles offset downwardly from the body and connected thereto by vertical portions, wheels on the spindles and a substantially triangular frame connected with the axle and comprising 80 side plates connected at their rear ends to the vertical portions of the axles and converging toward their forward ends, vertical plates connected to the front ends of the side plates and connected together in spaced relation, braces extending from the upper ends of the vertical plates to the body of the axle, a trailing wheel journaled on a vertical axis between the lower ends of the vertical plates, the plow supporting frame being substantially 85 triangular and comprising a central and side plates, the central plate extending forwardly between the vertical plates, each side plate being hinged to the central plate at the front end of the side plate, a plow 90 supporting beam adjustably connected with the central plate in rear of the connection of the side plates, a plow supporting beam hinged to the rear end of each side plate to swing on a vertical axis, a pair of connected 95 cross bars arranged transversely of the last-named beams at the rear ends of the side plates, the members of the pair being above and below the beams and the central plate, means on the wheel supported frame and 100 connected with the cross bars and with the central plate at the front end thereof for bodily lifting and lowering the plow supporting frame and for holding it in adjusted position, a detachable guiding connection 105 between the rear ends of the frames for guiding the plow supporting frame in its movement, said means comprising channel bars secured to the vertical portions of the axle, guide blocks at the ends of the cross 110 bars, and engaging the channel of the channel bars, and means on the central bar for simultaneously moving the rear plow beams toward and from each other.

2. In combination, a wheel supported 115 frame and a plow supporting frame detachably and adjustably connected therewith, the wheel supported frame comprising an axle consisting of a body and spindles offset 120 downwardly from the body and connected thereto by vertical portions, wheels on the spindles and a substantially triangular frame connected with the axle and comprising 125 side plates connected at their rear ends to the vertical portions of the axle and con- 130

- verging toward their forward ends, vertical plates connected to the front ends of the side plates and connected together in spaced relation, braces extending from the upper 5 ends of the vertical plates to the body of the axle, a trailing wheel journaled on a vertical axis between the lower ends of the vertical plates, the plow supporting frame being substantially triangular and comprising 10 a central and side plates, the central plate extending forwardly between the vertical plates, each side plate being hinged to the central plate at the front end of the side plate, a plow supporting beam adjustably 15 connected with the central plate in rear of the connection of the side plates, a plow supporting beam hinged to the rear end of each side plate to swing on a vertical axle, a pair of connected cross bars arranged trans- 20 versely of the last-named beams at the rear ends of the side plates, the members of the pair being above and below the beams and the central plate, means on the wheel supported frame and connected with the cross 25 bars and with the central plate at the front end thereof for bodily lifting and lowering the plow supporting frame and for holding it in adjusted position, a detachable guiding connection between the rear ends of the 30 frames for guiding the plow supporting frame in its movement, and means on the central plate and connected to the adjacent beams for simultaneously moving them toward and from each other.
- 35 3. In combination, a wheel supported frame and a plow supporting frame detachably and adjustably connected therewith, the wheel supported frame comprising an axle consisting of a body and spindles offset 40 downwardly from the body and connected thereto by vertical portions, wheels on the spindles and a substantially triangular frame connected with the axle and comprising side plates connected at their rear ends 45 to the vertical portions of the axles and converging toward their forward ends, vertical plates connected to the front ends of the side plates and connected together in spaced relation, braces extending from the upper 50 ends of the vertical plates to the body of the axle, a trailing wheel journaled on a vertical axis between the lower ends of the vertical plates, the plow supporting frame being substantially triangular and comprising 55 a central and side plates, the central plate extending forwardly between the vertical plates, each side plate being hinged to the central plate at the front end of the side plate, a plow supporting beam adjustably 60 connected with the central plate in rear of the connection of the side plates, a plow supporting beam hinged to the rear end of each side plate to swing on a vertical axis, means 65 on the wheel supported frame for bodily

raising and lowering the plow supporting frame, and means on the plow supporting frame for swinging the beams simultaneously toward and from each other.

4. In combination, a wheel supported frame and a plow supporting frame, said frames being substantially triangular and the wheel supported frame having a trailing wheel at the front thereof and an axle forming a base thereof, and comprising a body and downwardly offset spindles connected to the body by vertical portions, plow supporting beams hinged to the plow supporting frame at the base thereof, a pair of cross bars, the members of the pair being arranged above and below the beams, guide blocks connecting the ends of the bars, means on the wheel supported frame and connected with the cross bars and with the front ends of the said frames for bodily lifting and lowering the said frame and for holding it in adjusted position, and channel bars on the vertical portions of the axle and engaged by the guide blocks for guiding the frame in its movement, said bars being open at their lower ends to permit the disengagement of the blocks.

5. In combination, a wheel supported frame and a plow supporting frame, said frames being substantially triangular and arranged with their apices at the front, the plow supporting frame being within the wheel supported frame, and the wheel supported frame having a vertical guideway at its front end and channel-shaped guideways at the opposite ends of its base, the plow supporting frame having a forward draft extension passing through the guide way of the wheel supported frame, and having guide blocks engaging the channel bars, and means on the wheel supported frame and connected to the plow supporting frame for bodily lifting the same, said channel bars being open at their lower ends to permit the disengagement of the blocks.

6. In combination, a wheel supported frame and a plow supporting frame, said frames being substantially triangular and arranged with their apices at the front, the plow supporting frame being within the wheel supported frame, and the wheel supported frame having a guide-way at its front and guide-ways at the opposite end of its base, the plow supporting frame having a forward draft extension passing through the guide-way at the apex of the wheel supported frame, and having guide blocks engaging the guideways at the base, and means on the wheel supported frame and connected to the plow supporting frame for bodily lifting the same.

7. In combination, a wheel supported frame, and a plow supporting frame, said frames being substantially triangular and

arranged with their apices at the front, the plow supporting frame being within the wheel supported frame, and the wheel supported frame having a guide-way at its front and guide-ways at the opposite end of its base, the plow supporting frame having a forward draft extension passing through

the guide-way at the apex of the wheel supported frame, and having guide blocks engaging the guide-ways at the base.
